(57) **CLAIM**

The ornamental design for an electrosurgical device, as shown and described.

DESCRIPTION

FIG. 1 is a front side perspective view of the electrosurgical device, showing my new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines are included for the purpose of illustrating environmental structure and form no part of the claimed design.
